N. R. HOLCOMB,
KEY FASTENER,
APPLICATION FILED JAN. 8, 1919.

1,307,496.

Patented June 24, 1919.

Inventor

N. R. Holcomb

By Watson E. Coleman
Attorney

UNITED STATES PATENT OFFICE.

NOBLE R. HOLCOMB, OF ELDORADO, KANSAS.

KEY-FASTENER.

1,307,496.

Specification of Letters Patent. Patented June 24, 1919.

Application filed January 8, 1919. Serial No. 270,199.

To all whom it may concern:

Be it known that I, NOBLE R. HOLCOMB, a citizen of the United States, residing at Eldorado, in the county of Butler and State 5 of Kansas, have invented certain new and useful Improvements in Key-Fasteners, of which the following is a specification, reference being had to the accompanying drawings.

- 10 This invention relates to certain improvements in key fasteners, and it is an object of the invention to provide a novel and improved device of this general character which may be readily and conveniently engaged with a key when in a lock, so that said key is held against withdrawal, so that the key will serve as a plugging means for the key hole to prevent the forcing through said key hole of chloroform or kindred material 15 by persons desiring to make an unlawful entry.

A further object of the invention is to provide a novel and improved device of this general character which serves to hold the bolt against retraction in addition to holding the key against extraction.

The invention consists in the details of construction and in the combination and arrangement of the several parts of my improved key fastener whereby certain important advantages are attained and the device rendered simpler, less expensive, and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in front elevation illustrating a lock having a key fastener applied thereto constructed in accordance with an embodiment of my invention;

Fig. 2 is a fragmentary view partly in top plan and partly in section illustrating my improved device as herein set forth; and

Fig. 3 is a fragmentary view in side elevation with the key removed and the holding member in a second position.

As disclosed in the accompanying drawings, C denotes a casing of a lock of any ordinary or preferred type, and which includes a sliding bolt B. 1 denotes an opening or key hole in the casing C, and in which

a key K is adapted to be inserted in order to properly manipulate the bolt B. It is preferred that the key K be of a type provided at its outer end with a bow 2. A side plate 60 of the casing C is provided with an opening a adapted to register with a threaded opening b in the bolt B when the bolt B is at the limit of its outward movement or locking position.

3 denotes an elongated plate provided with a longitudinally disposed slot 4. Insertible through the slot 4 is a clamping screw 5 which is also adapted to be disposed through the opening a and to be engaged within the opening b in the bolt B when the bolt B is in its extended or locking position. The clamping screw 5 also serves to hold the plate 3 in applied position upon the casing C. H denotes an elongated flexible holding 75 member, preferably formed of metal, and which is riveted as at 6, or otherwise secured to an end portion of the plate 3. After the key K has been manipulated to extend the bolt B in locking position, the screw 5 is engaged within the opening b and the key K is adjusted to have its bow 2 vertically disposed as is particularly illustrated in Figs. 1 and 2 of the accompanying drawings. The holding member H is then inserted through 80 the bow 2 of the key K and the screw 5 rotated to clamp the plate 3 against movement. By this means it will be self evident that the key K is effectively held within the key hole or opening 1 and in a position to stop 85 or plug the hole or opening 1 against the passage of chloroform or kindred material therethrough as may be endeavored by a person desiring to gain unlawful entry. By having the member H flexible, it will be self 90 evident that the free end portion thereof may be properly adjusted in order to extend through the bow 2. It is also preferred that the free end portion of the member H be gradually extended or tapered to facilitate 95 its insertion through the bow 2.

From the foregoing description, it is thought to be obvious that a key fastener constructed in accordance with my invention is particularly well adapted for use by reason of the convenience and facility with which it may be assembled and operated, and it will also be obvious that my invention is susceptible of some change and modification without departing from the principles and 100 spirit thereof, and for this reason I do not wish to be understood as limiting myself

to the precise arrangement and formation of the several parts herein shown in carrying out my invention in practice except as hereinafter claimed.

5 What I claim is:

In combination with a plate and a slideable bolt, said plate and the bolt being provided with registering openings when the bolt is in its locking position, a clamping member 10 disposed through the openings of the plate

and bolt for holding the bolt against retrograde movement, and a key engaging means held to the casing by said clamping member.

In testimony whereof I hereunto affix my signature in the presence of two witnesses. 15

NOBLE R. HOLCOMB.
